UNITED STATES PATENT OFFICE

ERNEST DAVIS, OF SYRACUSE, NEW YORK, ASSIGNOR TO THE PROSPERITY COMPANY INC., OF SYRACUSE, NEW YORK, A CORPORATION OF NEW YORK

TWO-OPERATOR TWO-HAND CONTROL

Application filed February 18, 1931. Serial No. 516,785.

This invention relates to pressing machines such as garment or laundry presses and particularly to control means for the larger size pressing machines which require 5 two or more operators.

In large pressing machines which are operated by two operators, control means are often provided with four operating means, so that both operators will be required to 10 use both hands in order to close the press. This safety precaution prevents one operator from closing the press while the other operator may have one or both hands between the pressing elements. With such control 15 devices in the past it has been possible to close the press in a single step to a predetermined degree of pressure. It has not been possible however to close the press under light pressure for certain classes of work 20 or under heavy pressure for other classes of work, or to initially close the press under light pressure and later apply heavy pressure after a steaming or air blowing operation. The principal object of this invention 25 is to provide control means which will require the use of both hands of all the operators, such control means being operable to close the press under light pressure or under heavy pressure, in a single step, or to 30 close the press under light pressure and then apply heavy pressure as a second operating step. A further object of the invention is to provide control means including at least five operator operated devices, a combination 35 of four of which may be operated to close the press under light pressure, and a different combination of four of which may be operated to close the press under heavy pressure. 40

Other objects and advantages of the invention will appear and will be pointed out as the description proceeds.

The invention consists in the novel features and in the combinations and constructions hereinafter set forth and claimed.

In describing this invention, reference is had to the accompanying drawings in which like characters designate corresponding 50 parts in all the views.

Figure 1 is a side elevation of a pressing machine to which my invention is applied.

Figure 2 is a fragmentary view of the pressing machine shown in Figure 1.

Figure 3 is a schematic showing, mostly in 55 section, of the control mechanism embodying my invention.

This invention may be used with a pressing machine requiring more than two operators but is here illustrated as applied to a 60 two operator press. A pressing head 11 is carried by a yoke 12 which is pivotally mounted at 13 on upstanding back leg of a pressing machine frame 14. The yoke 12 is movable about the pivotal connection 13 to 65 move the pressing head 11 into and out of contact with a fixed pressing element or buck 16 to close and open the press. The buck 16 is supported by a neck 17 which is mounted on the pressing machine frame 14. 70

A fluid motor 20 is pivotally connected at 21 with the pressing machine frame 14 and the piston rod 22, of the fluid motor 20, is pivotally connected at 24 with the yoke 12. Operation of the fluid motor 20, in a manner 75 later to be described, will move the yoke 12 to close the press under light pressure.

A link 25 is pivotally connected at 26 with the yoke 12 and a link 28 is pivotally connected at its one end at 29 with the link 25, and at its other end at 30 with a link 32. The links 25 and 28 constitute a toggle which is moved into straightened position, to close the press, by a pull link 34. The pull link 34 is pivotally connected at 36 with the link 28 and is provided at its forward end with a cam follower 38 which operates in a guiding cam slot 40. 80

A fluid motor 42 is pivotally connected at 43 with the pressing machine frame 14. A piston rod 44, of the fluid motor 42, is pivotally connected at 45 with the forward end of the link 34. Operation of the fluid motor 42 in a manner later to be described, will move the cam follower 38 downwardly in the cam slot 40 and operate the pull link 34 to straighten the toggle to close the press under heavy pressure. The mechanism thus far described is of the conventional type and forms no part of the present invention. 95 100

The control mechanism, as shown in Figure 3, includes operator operated devices such as push buttons 51, 52, 53, 54 and 55. The push button 51 operates the valves in a valve casing 61, the motion of the push button being transmitted through a bell crank 62 and rocker arm 63 to a valve stem 64 which extends through the end of the valve casing 61. The valve stem 64 is formed on a normally open 10 exhaust valve 65 which is connected by a spacer rod 66 with a normally closed intake valve 67. A spring 68 holds the valves 65 and 67 in normal position. A spring 69 holds the bell crank 62 and push button 51 in normal position. Depression of the push button 51 will move the bell crank 62 and rocker arm 63 so that the rocker arm 63 will move the valve stem 64 to open the intake valve 67 and close the exhaust valve 65 in the valve 15 casing 61. The push button 52 transmits motion through a bell crank 70 and rocker arm 71 to operate an exhaust valve 72 which is located in a valve casing 73. This operating mechanism is similar to the mechanism 20 operated by the push button 51 and a spring 75, corresponding to the spring 69, holds the bell crank 70 and push button 52 in normal position. The valve casing 73 contains only one valve and no spring is necessary to 25 hold this valve in normal position.

The push button 53 operates against an arm 80 which is rigidly secured to a rock shaft 82. Arms 84 and 85, which are rigidly mounted at opposite ends of the rock shaft 30 82, actuate rocker arms 86 and 87. The rocker arm 86 contacts with the stem of an exhaust valve 90 which is located in a valve casing 92. The rocker arm 87 contacts with the stem of an exhaust valve 94 which is mounted 35 in a valve casing 96. Depression of the push button 53 will move the arm 80 to rotate the rock shaft 82 sufficiently to move the arms 84 and 85 and their respective rocker arms 86 and 87 sufficiently to close the exhaust valves 40 90 and 94, respectively. The push button 54 operates the valves in a valve casing 98. The valves in this valve casing 98 and the motion transmitting means between the valve casing 98 and the push button 54 are identical in 45 construction and operation with the valves and motion transmitting connections previously described for the valve casing 61 and push button 51. Further description of these parts seems unnecessary. The intake and exhaust valves in the valve casing 98 are designated by the reference characters 100 and 102, respectively.

The push button 55 operates the valves in a valve casing 105. These valves and the motion transmitting means through which they are operated by the push button 55 are identical with the valves and motion transmitting means previously described for valve casing 61 and push button 51. The valve casing 105 60 contains a normally closed intake valve 108

and a normally open exhaust valve 110. Further description of these valves or their operating mechanism is unnecessary.

The valve casing 61, 73, 92, 96, 98 and 105 are provided with diaphragm chambers 111, 112, 113, 114, 115 and 116, respectively. The diaphragm chamber 111 contains a diaphragm 118, and a plunger 119 which extends through one end of the diaphragm chamber 111 adjacent the lower end of the rocker arm 63. When pressure is applied behind the diaphragm 118 the plunger 119 will be operated against the rocker arm 63 to move the rocker arm 63 into position to operate the valves in the valve casing 61, or to hold the rocker arm 63 locked in such operated position. The other diaphragm chambers 112, 113, 114, 115 and 116 are provided with corresponding diaphragms and plungers for locking their respective rocker arms in operated position.

The fluid motor 20 includes a cylinder 121 containing a piston 122 which is rigidly secured to the piston rod 22. A port opening 124 is provided in the wall of the cylinder 121 at a point near one end of the stroke of the piston 122 so that the piston will uncover the port 124 at the time that the press reaches substantially closed position. The port opening 124 connects with a conduit 126 which is connected with the valve mechanism in a manner later to be described.

The fluid motor 42 includes a cylinder 131 containing a piston 132 which is rigidly mounted on the piston rod 44. A port opening 134 is provided in the wall of the cylinder 131 at a point near one end of the stroke of the piston 132 so that the piston 132 will uncover the port opening 134 when the press elements are together under heavy pressure. The port opening 134 communicates with a conduit 136 which is connected with the valve mechanism in a manner later to be described.

A valve casing 140 contains an exhaust valve 142 which is normally held in closed position by a spring 143. A valve stem 144 formed on the exhaust valve 142 extends through the end of the valve casing 140. An operating arm 145 is pivotally mounted at 146 on the valve casing 140 and the upper end of the operating arm 145 may be moved into contact with the valve stem 144 to open the exhaust valve 142. A valve casing 150 contains an exhaust valve 152 which is identical in construction and mode of operation with the exhaust valve 142 in the valve casing 140. A connecting arm 155 is secured to the operating arm 145 and to a corresponding operating arm 157 which is mounted on the valve casing 150. A release handle 160 is rigidly secured to the connecting arm 155 and movement of the release handle 160 will open both of the exhaust valves 142 and 152.

Connecting piping and operation of control mechanism

Working fluid, such as air, is supplied to 5 the valve casing 61 through a fluid supply line 161. As long as the intake valve 67 is closed no air can enter the system. Operation of the push button 51 will open the intake valve 67 and close the exhaust valve 65. 10 Working fluid may then pass through the fluid supply line 161, around the open intake valve 67, into a pipe 163 which connects with the valve casing 61 at a point between the valves 65 and 67. The pipe 163 connects 15 with the valve casing 105 and if the push button 55 is operated at the same time as the push button 51 the intake valve 108 will be open and air from the pipe 163 may flow around the open intake valve 108 and into a 20 pipe 165 which connects with the valve casing 105 at a point between the valves 108 and 110. The pipe 165 connects the valve casing 105 with the valve casing 92 but a branch pipe 167 connects the pipe 165 with 25 the fluid motor 20. From the above description it will be apparent that operation of the push buttons 51 and 55 establishes communication between the fluid supply line 161 and the fluid motor 20. In order to compel both 30 operators to use both hands, connections are provided so that it is necessary to also operate the push buttons 52 and 53. A pipe 170 connects the pipe 163 with the valve casing 73 and unless the push button 52 is operated 35 to close the valve 72 working fluid from the pipe 163 will be free to escape through the valve casing 73 and open exhaust valve 63 thus preventing sufficient pressure from being supplied to the fluid motor 20 to operate 40 the press. Operation of the push button 53 is necessary in order to close the exhaust valve 90 in the valve casing 92 and thus prevent working fluid in the pipe 165 from escaping through the valve casing 92 and open 45 exhaust valve 90.

Operation of the push buttons 51, 52, 53 and 55 will therefore supply air under pressure to the fluid motor 20 to move the piston 122 therein and bring the pressing elements together under light pressure, as previously described. When the pressing elements come in contact, or are substantially in contact, the piston 122 will uncover the port opening 124 and air will flow through this port opening 124 to the conduit 126 which is connected by a pipe 175 with pipes 176 and 177. The pipe 176 supplies air to the diaphragm chamber 116 and the pipe 177 is provided with a branch pipe 179 which supplies air to the 60 diaphragm chamber 113. A check valve 180 is provided at one end of the pipe 177 and permits air to flow in the direction of the arrow but prevents air from flowing in the other direction. A pipe 182 connects the 65 check valve 180 with a pipe 184 which leads

to the diaphragm chamber 111. A branch pipe 186 connects the pipe 184 with the diaphragm chamber 112. When the piston 122 uncovers the port opening 124 and air is supplied to the diaphragm chambers 111, 112, 113 and 116, as above described, the valves in the valve casings 61, 73, 92 and 105 will be locked in operated position and the press will remain closed under light pressure. 70

With the press closed under light pressure one operator may apply final heavy pressure by depressing the push buttons 53 and 54. The operation of the push button 54 will open the valve 100 in the valve casing 98 and air from the pipe 163 will flow through a pipe 185, which connects the pipe 163 with the valve casing 98, around the open intake valve 100 and into a pipe 187 which connects with the valve casing 98 at a point between the valves 100 and 102. The pipe 187 is connected at its other end with the valve casing 96 and a branch pipe 189 connects the pipe 187 with the fluid motor 42. It is necessary to operate the push button 54 in order to supply air to the pipe 187 and it is necessary to operate the push button 53 to close the exhaust valve 94 in order to prevent air from escaping from the pipe 187. 80

When the push buttons 53 and 54 are operated, as above described, air under pressure will be supplied through the branch pipe 189 to the fluid motor 42 to operate the piston 132 therein and apply final heavy pressure to the pressing elements through the actuating mechanism previously described. The piston 132 will have moved down in the cylinder 131 during the closing of the press under influence of the fluid motor 20 but the air supplied to the fluid motor 42 will cause the piston 132 to move downwardly still further and uncover the port opening 134. When the piston 132 uncovers this port opening 134 air will flow through the port opening 134 into the conduit 136 which is connected by a pipe 190 with the diaphragm chamber 115. A branch pipe 192 connects the pipe 190 with the diaphragm chamber 114. When the piston 132 uncovers the port opening 134 to supply air to the diaphragm chambers 114 and 115, as above described, the valves in the valve casings 96 and 98 will be locked in operated position and the press will remain closed under heavy pressure. 90

When the press is open the operators may control the operating mechanism to close the press under heavy pressure in a single operating step by depressing the push buttons 51, 52, 53 and 54. Operation of the push button 51 is necessary to supply air to the pipe 163 as in the case of light pressure operation, and operation of the push button 52 is necessary in order to close the exhaust valve 72 and prevent air in the pipe 163 from escaping through the branch pipe 170, valve casing 73, and past 105 110 115 120 125 130

the open exhaust valve 72. Operation of the push button 54 will permit air to flow from the pipe 163, through the pipe 185, around the open intake valve 100, through the pipe 187, and branch pipe 189 to the fluid motor 42. Operation of the push button 53 will prevent air in the pipe 187 from escaping through the valve casing 96 and past the open exhaust valve 94. Thus operation of the push buttons 51, 52, 53 and 54 will cause the press to close under heavy pressure in a single step and when the piston 132 uncovers the port 134 air will flow through the conduit 136, and pipe 190 to the diaphragm chamber 115 to lock the valves in the valve casing 98 in operated position. Air will also flow from the pipe 190 through the pipe 192 to the diaphragm chamber 114 to lock the valve in the valve casing 96 in operated position. The pipe 190 is connected by a pipe 194 with a check valve 195 which permits air to flow in the direction indicated by the arrow but prevents the flow of air in the opposite direction. Thus air may flow from the pipe 194 through the check valve 195 and through a pipe 198 which connects with the pipes 182 and 184. The pipe 184 connects directly with the diaphragm chamber 111, and through the branch pipe 186 with the diaphragm chamber 112 so that air from the pipe 190 may pass through the pipe 194, check valve 195, pipe 198, and pipe 184 and branch pipe 186 to the diaphragm chambers 111 and 112 to lock the valves in the valve casings 61, and 73 in operated position. When the piston 132 uncovers the port opening 134 therefore, the valves in the valve casings 61, 73, 96 and 98 will be locked in operated position and the press will remain closed under heavy pressure. The press may be opened from light pressure position or from heavy pressure position by operating the release handle 160 to open the exhaust valves 142 and 152. The valve casing 140 is connected by a pipe 199 with the pipe 186 and the valve casing 150 is connected by a pipe 200 with the pipe 192. Since the pipes 186 and 192 are in communication, by connections previously described, with all of the diaphragm chambers, the opening of the exhaust valves 142 and 152 will permit air to exhaust from all of the diaphragm chambers and thus release any of the valves which are held locked in operated position. The port openings 124 and 134 in the cylinders 121 and 131, respectively, are of small diameter so that air cannot flow through these port openings to the diaphragm chambers as fast as it will exhaust through the open conduits and open exhaust valves 142 and 152.

From the foregoing description it will be apparent that the press may be closed under light pressure by operating a group of four push buttons and that the press will lock closed under light pressure. It will be fur-

ther apparent that other control means may be operated to apply final heavy pressure, and that the press can be closed from open position to heavy pressure in a single operating step by operating a group of four push buttons which includes certain of the push buttons used when closing the press under light pressure. The invention is illustrated in its preferred embodiment but changes and modifications may be made without departing from the spirit of the invention as set forth in the appended claims.

What I claim is:

1. In a pressing machine in combination cooperative pressing elements, one of which is movable with respect to the other; actuating means for the movable pressing element including motor means for closing the press under light and under heavy pressure; a power feed line; a first pair of operator-operated control devices connected to the motor means to control the supply of power thereto to close the press under light pressure; a second pair of operator-operated control devices connected to the feed line and to the first and second pairs of control devices to control the supply of power thereto, whereby operation of the first and the third pairs of the control devices is required to close the press under light pressure and operation of the second and the third pairs of control devices is required to close the press under heavy pressure.

2. In a pressing machine in combination cooperative pressing elements, one of which is movable with respect to the other; actuating means for the movable pressing element including a first motor means for closing the press under light pressure and a second motor means for closing the press under heavy pressure; a power feed line; a first pair of operator-operated control devices connected to the light pressure motor means to control the supply of power thereto; a second pair of operator-operated control devices connected to the heavy pressure motor means to control the supply of power thereto; and a third pair of operator-operated control devices connected to the feed line and to the first and second pairs of control devices to control the supply of power thereto.

3. In a pressing machine in combination cooperative pressing elements, one of which is movable with respect to the other; actuating means for the movable pressing element including motor means for closing the press under light and under heavy pressure; a power feed line; a first pair of operator-operated control devices connected to the motor means to control the supply of power thereto to close the press under light pressure; a

second pair of operator-operated control devices connected to the motor means to control the supply of power thereto to close the press under heavy pressure; and a third pair of operator-operated control devices connected to the feed line and to the first and second pair of control devices to control the supply of power thereto, locking means associated with each control device of the first and third pairs and operable to hold the same in operative position; means connected to the locking means to operate the locking means upon closing of the press under light pressure; and operator-operated means for restoring the locking means to normal position.

4. In a pressing machine in combination with cooperative pressing elements, one of which is movable with respect to the other; actuating means for the movable pressing element including motor means for closing the press under light and under heavy pressure; a power feed line; a first pair of operator-operated control devices connected to the motor means

to control the supply of power thereto to close the press under light pressure; a second pair of operator-operated control devices connected to the motor means to control the supply of power thereto to close the press under heavy pressure; and a third pair of operator-operated control devices connected to the feed line and to the first and second pair of control devices to control the supply of power thereto, locking means associated with each control device and operable to hold the same in operated position; means connected to the locking means to operate the locking means associated with the first and third pairs of control devices upon closing of the press under light pressure and to operate the locking means associated with the second pair of control devices upon closing of the press under heavy pressure; and operator-operated means for restoring the locking means to normal position.
